N. S. Vedder and Ezra Ripley, of Troy, N.Y.
Assignors to

N. S. Vedder, aforesaid.
Letters Patent No. 1661, dated Sept. 23, 1862.

The schedule referred to in these Letters Patent and making part of the same.

To all whom it may concern:

Be it known that we, N. S. Vedder and Ezra Ripley, each of the City of Troy, in the County of Rensselaer, and State of New York, have jointly invented or produced a new and original ornamental design for a Stove Plate, or plates, of which the following is a full and exact description, reference being had to the annexed photographic drawings, in which -

Fig. 1. is a front plate.

Fig. 2. a side plate, and

Fig. 3. a back plate of a stove having our said ornamental design.

The distinctive feature of our said ornamental design is the arrangement, upon the panel of a stove plate, of the swelling
